(57) **CLAIM**

The ornamental design for a drone body, as shown and described.

DESCRIPTION

FIG. 1 perspective view of the drone body showing our new ornamental design.

FIG. 2 another perspective view of the drone body with an unclaimed drone battery pack attached thereto.

FIG. 3 is a back elevation view thereof.

FIG. 4 is a front, plan view thereof.

FIG. 5 is top, plan view thereof.

FIG. 6 is bottom, plan view thereof.

FIG. 7 is a left elevational view thereof; and,

FIG. 8 is a right elevational view thereof.

The broken lines in the drawings depict portions of the drone body that form no part of the claimed design.

1 Claim, 5 Drawing Sheets
